ATTORNEY

UNITED STATES PATENT OFFICE.

THOMAS CALDWELL, OF PITTSBURGH, PENNSYLVANIA.

1,107,029.

WRENCH.

Specification of Letters Patent.

Patented Aug. 11, 1914.

Application filed August 5, 1913. Serial No. 783,176.

To all whom it may concern:

Be it known that I, THOMAS CALDWELL, a citizen of the United States of America, residing at Pittsburgh, in the county of Allegheny and State of Pennsylvania, have invented certain new and useful Improvements in Wrenches, of which the following is a specification, reference being had thereto in to the accompanying drawing.

This invention relates to wrenches, and the objects of my invention, are, first, to provide a quick acting wrench that has a novel adjustable jaw; second, to provide a nut wrench that has the operating mechanism thereof concealed whereby the wrench is not liable to injury by ordinary use; third, to provide a wrench having an adjustable jaw that can be shifted in one direction without operating the mechanism of said wrench, and fourth, to provide a strong and durable wrench consisting of comparatively few parts that are inexpensive to manufacture, easy to assemble and highly efficient for the purposes for which they are intended.

With the above and other objects in view the invention resides in the novel construction, combination and arrangement of parts to be hereinafter more specifically described and then claimed.

Reference will now be had to the drawing, wherein:—

Figure 1 is a side elevation of the wrench, Fig. 2 is a similar view partly broken away and partly in section, Fig. 3 is a perspective view of a detached plate, and Fig. 4 is a perspective view of a detached adjustable jaw.

A wrench in accordance with this invention comprises a shank 1 that is rectangular in cross section. The inner end of the shank constitutes a handle and the outer end thereof is provided with an integral jaw 2 that presents a flat gripping surface 3 at right angles to the front side of the shank. The rear side of the shank has transverse ratchet teeth 4.

Slidably mounted upon the shank 1 is an adjustable jaw body 5 having the front side

thereof provided with a jaw 6 presenting a flat gripping surface 7 that confronts and coöperates with the gripping surface 3 of the jaw 2. The rear side of the jaw body 5 has a rectangular opening 8 and pivotally mounted in said opening by a transverse pin 9 is a pawl 10 for engaging the ratchet teeth 4 of the shank 1. The pawl 10 has an arm 11 that is engaged by a flat compression spring 12 secured by a screw 13 or other fastening means to the rear side of the jaw body 5. This compression spring holds the pawl 10 normally in engagement with the teeth 4 of the shank 1.

The rear side of the adjustable jaw body 5 is stepped, as at 14 and secured to the rear side of said jaw body and closing the opening 8 is a detachable plate 15 that is held in engagement with the jaw body 5 by screws or other fastening means. Centrally of the plate 15 is an opening 16 and slidably mounted in said opening is a push pin 17 that has the inner end thereof provided with a rounded detachable head 18. The head 18 also prevents the push pin from becoming accidentally displaced relatively to the plate 15. By pushing inwardly upon the pin 17 the pawl 10 can be shifted out of engagement with the shank 1, whereby the jaw 6 can be opened relatively to the jaw 2. To close the jaw 6 it is only necessary to push the jaw body 5 toward the outer end of the shank.

One embodiment of my invention has been illustrated, but it is to be understood that the structural elements are susceptible to such variations and modifications as fall within the scope of the appended claim.

What I claim is:—

A wrench comprising a shank having a fixed jaw and a toothed rear edge, a jaw body slidably mounted on the shank and having its rear side stepped and arranged with an opening, a pawl pivotally mounted in the opening of the jaw body for engaging the teeth of the shank and having an arm, an inset plate formed on the rear side of the jaw body and having a pocket, a flat compression spring extending into said

pocket and secured to the jaw body and extending in said openings to engage said arm for maintaining the pawl in engagement with said teeth, a push pin mounted in said plate and having a head at its inner and outer plate and the inner head being capable of engaging said arm for shifting the pawl against the action of the spring and

a screw passing through said plate for securing the same to the jaw body.

In testimony whereof I affix my signature in the presence of two witnesses.

THOMAS CALDWELL.
